UNITED STATES PATENT OFFICE.

HUGH J. SMITH, OF BROOKLYN, NEW YORK.

WINDOW CONSTRUCTION.

Application filed July 17, 1922. Serial No. 575,563.

To all whom it may concern:

Be it known that I, HUGH J. SMITH, a citizen of the United States, and a resident of the city of New York, borough of Brooklyn, in the county of Kings and State of New York, have invented a new and Improved Window Construction, of which the following is a full, clear, and exact description.

10 This invention relates to a window construction, and has for an object the provision of a construction such that the windowpane in a sash can be readily moved with respect to the sash so that a person 15 standing within a room can clean both sides of the window without sitting on the sill or standing on the outside of the window.

Another object resides in the provision of 20 a construction in which the above-mentioned object is achieved while yet providing a construction which is neat, compact and durable.

A further object resides in the particular 25 construction and arrangement of parts which are hereinafter described and claimed and shown in the accompanying drawings.

The invention is illustrated in the drawings, of which—

30 Figure 1 is a perspective view of a window frame showing two sashes, from one of which the windowpane has been moved out so that both sides of the window can be cleaned by a person standing within the 35 room.

Fig. 2 is a section taken on the line 2—2 of Fig. 1.

Fig. 3 is an end elevation of the upper 40 end of the window frame showing the windowpane in an open or abnormal position.

The form of the invention shown in the drawings is a preferred form, although it is understood that modifications in the construction and arrangement of the parts and in the character of the materials used may be adopted without departing from the spirit of the invention.

In cleaning windows it is generally necessary for a person to stand or sit on the window sill in order to reach out and clean the outside of the panes. To eliminate this necessity, I have provided in each sash a pivoted frame which supports the pane and which can be pivotally moved away from the frame so that a person can get

at both sides of the pane. In the preferred form of my invention as illustrated in the drawings, the construction relates to a window sash having rails 1 and 2 and stiles 3 and 4. To the rails at one side of the frame, I pivot metal plates 5 and 6. The pivotal connection between the plates 5 and 6 and the rails 1 and 2 may be made in any suitable manner. These plates are spaced apart the full height of the sash opening and are adapted to receive a windowpane 7 which may be fastened thereagainst in any desired manner. Along the front of the windowpane at its top and bottom edges, and suitably connected in any desired manner to the members 5 and 6, I dispose molding portions 8 and 9. These molding portions are provided with flat shoulders on which the edges of the pane 7 rest. The sides of the pane are held between the molding portions 8 and 9 and the plates 5 and 6. Without any further consideration it will be seen that the members 5 and 6 and molding members 8 and 9, together with the pane of glass 7, form a frame pivotally connected to the rails of a window sash and which can be moved out into the room, as shown in Fig. 1, so that a person can get at both sides of the pane. The upper and lower edges of this frame are provided with molding members so that when it is in its normal position within the sash the frame will have a substantially finished appearance.

In order to complete the effect of molding, I provide a pair of lateral molding members 10 and 11. These are adapted in their closed position to lie along the vertical sides of the opening and complete the substantially finished appearance of the construction. At the upper and lower ends of the lateral molding member 10, I connect in any suitable manner horizontally disposed flat bars 12 and 13. These bars are pivotally connected respectively to the upper edge of the rail 2 and the lower edge of the rail 1. To the upper and lower edges of the lateral molding member 11 I connect similar bars 14 and 15 which are in turn respectively connected to the upper edge of the lower rail 2 and the lower edge of the upper rail 1. The horizontal length of the bars 12 and 13 is greater than the horizontal length of the bars 14 and 15 because the pivot pins of the latter bars are nearer one vertical edge of the pane of glass than are the pivot pins of the other bars. This construction

permits of a proper angle of opening. Each pair of bars and its respective lateral molding member forms a swinging frame which can be pulled out and by reason of which the bars, particularly the lower ones 12 and 14, tend to support the lower edge of the glass for the lower channel member 5.

The bars 12 to 15, inclusive, may be suitably connected to the lateral molding members 10 and 11, respectively, by having their end portions turned down along the edges of these molding members and connected thereto by any suitable means.

When the window pane and its supporting frame bars are moved into their normal position within the sash then the molding frame members can be moved into position to give the appearance of a substantially finished molding for the pane. When it is desired to open the pane for cleaning it is merely necessary to pull out the lateral molding members which move pivotally around the pivot points of their supporting bars to any desired position whereupon the free end of the pane of glass can be grasped to move it around the pivot points of its supporting frame bars 5 and 6.

The detailed manner in which the various connections are made is a matter of no particular importance to the essence of the invention, many variations in the detail construction being permissible while yet lying within the general scope of the invention.

It will be seen, therefore, that it is a very

simple matter to move the windowpane to a position whereby both sides of it can be readily cleaned by a person standing within the room and that this action can take place regardless of the position of the sash and without in any way affecting the relation of the sash to the window frame. The same construction, of course, can be applied to either one or both of the sashes.

What I claim is:

1. In a window sash construction, a windowpane pivotally connected to the sash, vertical molding members normally disposed at the vertical sides of the pane, and supporting bars for said molding members connected to the sash and movable outwardly, said supporting bars and molding members forming pivoted frames adapted to be swung out to support the glass when the glass is swung outwardly.

2. In a window sash construction, a pair of frame members pivoted to the sash, a windowpane supported between said members, fixed molding members disposed along the upper and lower edges of the pane, movable molding members disposed along the lateral edges of the pane, and pivoted supporting bars for said lateral molding members connected to the rails of the sash, said supporting bars and lateral molding members acting as pivoted frames to be swung out to support the pane when it is swung outwardly.

HUGH J. SMITH.
